(57) CLAIM

The ornamental design for a video tape cassette, as shown and described.

DESCRIPTION

FIG. 1 is a side elevational view of a video tape cassette showing my new design, the side opposite that shown in FIG. 1 being the mirror image thereof;

FIG. 2 is a top plan view thereof;

FIG. 3 is a bottom plan view thereof;

FIG. 4 is an end elevational view thereof from the left of FIG. 2;

FIG. 5 is an end elevational view thereof from the right of FIG. 2; and,

FIG. 6 is a top perspective view thereof.

The material shown in broken line in FIG. 3 forms no part of the present invention and is disclaimed.
